UNITED STATES PATENT OFFICE.

OLIVER W. BOZZETT, OF BROOKLYN, NEW YORK, ASSIGNOR OF ONE-HALF TO JAMES J. JOYCE, OF ANNAPOLIS, MARYLAND.

SELF-ACTING NAVAL-DEFENSE MINE.

1,248,799,

Specification of Letters Patent.

Patented Dec. 4, 1917.

Application filed November 21, 1916. Serial No. 132,645.

To all whom it may concern:

Be it known that I, OLIVER W. BOZZETT, a citizen of the United States, and a resident of Brooklyn, in the county of Kings 5 and State of New York, have invented a certain new and useful Improvement in Self-Acting Naval-Defense Mines, of which the following is a specification.

My present invention relates to self-acting 10 naval or coast defense mines of the submarine type.

The principal objects of my invention are first, to provide mines of the character described which are positive in action when 15 struck by a colliding vessel; second, mines embodying frangible contact members or horns, and apparatus associated therewith that when one or more of the horns are submerged and broken, the mine is exploded; 20 third, mines embodying horns of the character described so constructed that they will not collect marine vegetation at the vital portions even though submerged for a very long period of time; fourth, mines which 25 may be transported with safety or used in practice without danger of casual explosion; fifth, mines embodying a firing chamber which is set into action by the ingress of water to the chamber through a broken contact horn when submerged; sixth, mines 30 which are simple in construction, easily assembled, and hence inexpensive to manufacture; and, seventh, mines which may be readily recovered after they have been anchored for operation, by use of suitable dragging apparatus without the danger of the mines exploding on the surface of the water.

Other objects and advantages of my invention will appear in the following detailed 40 description, taken in connection with the accompanying drawings, forming a part of this specification, and in which drawings:

Figure 1 is a side elevation of a mine constructed according to my invention.

Fig. 2 is a central vertical sectional view through the mine, parts being shown in elevation to simplify the disclosure.

Fig. 3 is a top plan view of a receptacle 50 for an ignitable substance.

Fig. 4 is a sectional view on the line 4-4 of Fig. 2 through a receptacle for quick ignition substance.

Fig. 5 is a longitudinal sectional view

through a contact piece or horn of the mine, 55 and associated parts.

Fig. 6 is a sectional view on the line 6-6 of Fig. 5.

In the drawings, where similar characters refer to similar parts throughout the 60 views; A designates a water-tight case, preferably globular in shape, and in the example shown including a main body B and a detachable cover C; D a housing in said case comprising a base E, a receptacle F for an 65 ignitable substance, a receptacle G for quick ignition substance, and a receptacle H for high explosives; J conveyers for water from the exterior of said case to said housing and in the example shown, to the receptacle F; 70 and, K frangible closures for said conveyers exteriorly of said case and in the example shown in the form of horns. If desired valves L may be provided in conveyers J and said conveyers may be formed to provide 75 water traps M.

Referring first to the case A, as shown, the cover C may be secured to the main body B, as by bolts 7 passing through a flange 8 of the cover and entering a flange 9 at the 80 upper portion of body B, a gasket 10 being interposed between the flanges 8 and 9. A device 11, such as a ring is secured to the lower portion of body B to facilitate anchorage of the mines in place, while the 85 cover C may be provided with a similar device 12 to facilitate planting of the mines and the placing or removal of the cover C with respect to body B.

Referring now to the magazine or housing D, the base E may be in the form of a cylindrical body welded or otherwise secured to the interior of case A at its lower portion and is hollow to provide a well 13. A diaphragm 14 may be secured in the hollow 90 of the base providing a false bottom for the well and a dead air-space 15 therebelow,—this for preventing water of condensation gaining access to the well 13. The receptacle F may comprise a hollow cylindrical main body 16, a reticulate bottom 17 and a plurality of nipples 18 projecting from its exterior and radially disposed, these nipples being welded or otherwise secured to the body 16 with their ways spaced a suitable distance above the bottom 17 as is clearly shown in Fig. 2 of the drawings. This receptacle is adapted to receive an 100 105

ignitable substance 19, such as calcium phosphid or other suitable substance which rests upon the bottom 17 and has its upper surface in close proximity to the ways 20 of 5 nipples 18. The receptacle D may comprise a main body 21 cylindrical in shape, and provided with a semi-globular head 22 and an exteriorly disposed annular flange 23 intermediate its ends; and, a reticulate bottom 10 tom 24. Above the flange 23, the body 21 is provided with perforations 25. This receptacle is adapted to receive quick ignition substance 26, such as black powder which rests upon the reticulate bottom 24 and is 15 disposed with its upper surface adjacent the perforations. As to the receptacle H it is relatively larger than the receptacles F and G and may be what is known in the art as a "TNT tank" being adapted to receive 20 a high explosive composition 27 including gun cotton.

The receptacle F may be in screw-threaded engagement with base E as clearly shown in Fig. 2 of the drawings, while the receptacle D may be in superposed relation to and in screw-threaded engagement with receptacle F. The receptacle H may be detachably secured to receptacle D as by bolts 28 passing through flange 23 and entering an 30 enlarged portion 29 at the mouth of receptacle H. If desired, this last-mentioned receptacle may be provided with a handle 30 to facilitate transportation and placing of the receptacle as hereinafter set forth.

35 The substance 19 is of that nature to be ignitable by an admixture of water, such water finding its way to receptacle F through the conveyers J which may comprise a socket 31 welded or otherwise secured 40 to the case A and extending from its exterior; a pipe 32; and, suitable unions 33 and 34 disposing pipe 32 in conducting communication with the way 35 of socket 31 and the way 20 of a nipple 18, respectively, as is 45 herein shown in Fig. 2 of the drawings. In the present example I have shown the pipe 32 so formed as to provide traps M below the level of way 20, and valves L interposed in the pipe between their connections with 50 the case A and housing G, the function of these valves being to close the pipes against ingress of water while the mines are being transported, or when used in practice although the valves may be dispensed with if 55 desired.

The conveyers J are arranged so that those portions at the body B of the case are at the upper portion thereof, or, in other words, above the central horizontal plane of 60 the case, and the sockets 31 are arranged, in the example shown, in circumferentially extending rows, one row being above the other as is clearly shown in Fig. 1 of the drawings.

65 Each socket 31 is adapted to receive a frangible closure or horn K. Referring

more particularly to Figs. 5 and 6, it is preferred to construct each contact or closure so as to comprise a metallic base 36 provided with an axial way 37; a hollow glass horn 38 with its open end portion hermetically 70 sealed in way 27, a suitable filler 39, such as cementitious material being interposed between the horn and the base; and, a moisture-proof coating 40, such as wax, within the hollow of the horn. This horn is preferably of tubular shape, closed at one end and made of glass, about the thickness of the ordinary water glass now used on water boilers. This horn, presenting a glazed surface exteriorly of the mine will not collect 80 marine vegetation or otherwise foul from use, and the vital portions are at all times exposed for engagement with the colliding vessel. The base 36 may be provided with screw threads 41 having engagement with 85 screw threads 42 of socket 31 and when turning the closure into operative relation to the conveyers J, a gasket 43 may be interposed between a shoulder 44 of the base 36 and the outer face of sockets 31 as is clearly shown 90 in Fig 5 of the drawings. Thus, the hollow of the horn 38 is in communication with the way 35 of sockets 31 and hence in communication with the interior of housing D at receptacle F.

95 When assembling the mine, with the cover C removed from operative relation to the main body B the receptacle F, containing the ignitable substance 19 may be turned into place, in fluid-tight engagement with the base E. The pipes 32 may be then secured in operative relation to their respective sockets 31 and nipples 18 of receptacle F. This may be followed by turning the receptacles G and H into operative relation to the receptacle F, whereafter the cover C may be placed in fluid-tight engagement with the main body B. The closures K may be then turned into operative relation to the sockets 31, and with the valves L, if provided, in an 100 open position, the mine is in readiness for 105 planting.

110 It is to be observed that the mines may be stored in an assembled condition except for the receptacles G and H, forming the high explosive portion of the magazine and there is no danger of premature explosion. Also, with the valves L closed, the mine may be transported without disposing the closures K in operative relation to the conductors J, 115 and there is little danger of casual exploding of the mine.

120 The action of the mine is as follows: Having been submerged and anchored in place, as is now common practice, any colliding vessel moving at the rate of two knots or more will break one or more of these frangible horns 38, whereupon water will flow through one or more of the conductors J into the receptacle F and the admixture 125

of the ignitable substance 19 and the water will create a flame. Any excess of water will drain through the substance 19 and find its way to well 18. The flame will ignite the 5 powder or other substance 26 in receptacle G, which in turn will set off the high explosive 27 in receptacle H.

It is to be observed that the housing D is so arranged with respect to the case A 10 that any particles of condensation which collect at the interior of the case will not find its way to mix with the substance 19. Should any condensation occur within the conductors J, it will be collected in the traps 15 M where such are provided. The possibility of condensation accumulating in the conductors is remote since, by the provision of the moisture-proof coating in the hollow of horns 38, condensation will not accumulate 20 late at such portion of the mine, which is directly associated with the magazine and exposed more directly to the water.

It is preferred to so construct the mine that its upper portion is relatively heavier 25 than the lower portion so that when it is desired to recover a mine by the usual practice of dragging, when the mine is released from its anchor, it will come to the surface of the water with the cover C lowermost 30 and the receptacle F above the normal water-line. Hence, should any of the horns 38 become broken, the mine will not be set off owing to the inability of the water to find its way above the normal water level.

35 I desire to lay much stress upon the fact that mines constructed according to my invention may be planted in the water for a considerable length of time without the liability of the mines becoming ineffective as 40 the result of marine growth, since such will not adhere to the closures K presenting a glazed surface exteriorly of the mine at its vital portions. Since the mine is dependent upon the introduction of water into the 45 magazine for the purpose of firing, it may be transported with safety, and assemblage is facilitated by the arrangement of the receptacles F, G and H, mounted upon the base E in the manner substantially hereinbefore set forth.

Changes in details may be made without departing from the spirit or scope of my invention; but,

I claim:

- 55 1. In a defense mine, the combination of a case, a receptacle for high explosive, a receptacle for quick ignition substance, a receptacle for ignitable substance in said case, said receptacles communicating, a plurality of frangible hollow contact horns carried by said case at its exterior, and conveyers for water in communication with said horns and said third-mentioned receptacle.
- 60 2. In a defense mine, the combination of a case, a receptacle for high explosive, a re-

ceptacle for quick ignition substance, a receptacle for ignitable substance in said case, said receptacles communicating, a conveyer for water in communication with said third-mentioned receptacle and extending exteriorly of said case, and a frangible closure for said conveyer exteriorly of said case.

3. In a defense mine, the combination of a case, a receptacle for high explosive, a receptacle for quick ignition substance, a receptacle for ignitable substance, said receptacles inclosed within said case and communicating, a plurality of frangible hollow contact horns carried by said case at its exterior, and conveyers for water in communication with said horns and said third-mentioned receptacle.

4. In a defense mine, the combination of a case, a receptacle for high explosive, a receptacle for quick ignition substance, a receptacle for ignitable substance, said receptacles inclosed within said case and communicating, a conveyer for water in communication with said third-mentioned receptacle and extending exteriorly of said case, and a frangible closure for said conveyer exteriorly of said case.

5. In a defense mine, the combination of a case, a housing in said case, a destructive agent in said housing adapted to be set off by the action of water in said housing, a plurality of pipes leading from the upper portion of said case to said housing, each of said pipes provided with a trap below the level of its ingress to said housing, and frangible closures for said pipes exteriorly of said case.

6. In a defense mine, the combination of a case, a housing in said case, a destructive agent in said housing adapted to be set off by the action of water in said housing, a plurality of pipes leading from the upper portion of said case to said housing, each of said pipes provided with a trap below the level of its ingress to said housing, and a valve intermediate the wall of said case and said housing, and frangible closures for said pipes exteriorly of said case.

7. In a defense mine, the combination of a case including a main body and a cover adapted to be secured to said main body in a water-tight manner, a base secured to the interior of said case at its lower portion and providing a well, a receptacle for substance ignitable by admixture of water, in screw-threaded engagement with said base and communicating with said well, a receptacle for quick ignition substance mounted upon and in screw-threaded engagement with said first-mentioned receptacle and in communication therewith, a receptacle for high explosives secured to said second-mentioned receptacle and in communication therewith, a conveyer for water in communication with said first-mentioned

4
receptacle and the exterior of said case, and a frangible closure for said conveyer exteriorly of said case.

8. In a defense mine, the combination of 5 a case including a main body and a cover adapted to be secured to said main body in a water-tight manner, a base secured to the interior of said case at its lower portion, and a dead air-space below said well, a receptacle for substance ignitable by admixture of water, in screw-threaded engagement with said base and communicating with said well, a receptacle for quick ignition substance surmounted upon and in screw-threaded engagement with said first-mentioned receptacle and in communication therewith, a receptacle for high explosives secured to said second-mentioned receptacle and in communication therewith, a conveyer 15 for water in communication with said first-mentioned receptacle and the exterior of said case, and a frangible closure for said conveyer exteriorly of said case.

9. As an article of manufacture, a contact 20 for mines comprising a metallic base provided with screw threads and an axial way, a hollow glass horn hermetically sealed to said base with its hollow open to the said way, and a moisture-proof coating in the 25 hollow of said horn.

10. As an article of manufacture, a contact for mines comprising a base provided with a way, a hollow horn presenting a glazed surface at its exterior, hermetically sealed to said base with its hollow open to said way, and a moisture-proof coating in the 30 hollow of said horn.

11. As an article of manufacture, a hollow glass horn-like contact member for 35 mines, and a moisture-proof coating in the hollow of said member.

12. As an article of manufacture, a contact for mines comprising a metallic base provided with screw threads and an axial way, a hollow glass horn hermetically 40

sealed to said base with its hollow open to said way, and a wax coating in the hollow of said horn.

13. As an article of manufacture, a contact for mines comprising a base provided 45 with a way, a hollow horn presenting a glazed surface at its exterior, hermetically sealed to said base with its hollow open to said way, and a wax-coating in the hollow of said horn.

14. As an article of manufacture, a hollow glass horn-like contact member for 50 mines, and a wax coating in the hollow of said member.

15. In a defense mine, a magazine comprising a receptacle for an ignitable substance, a receptacle for quick ignition substance above said first-mentioned receptacle and provided with a reticulate bottom, and a receptacle for high explosives above said 55 second-mentioned receptacle and in communication therewith.

16. In a defense mine, the combination of a case, a base in said case secured to its bottom, a receptacle for an ignitable substance above said base and provided with a reticulate bottom, a receptacle for quick ignition substance above said first-mentioned receptacle and provided with a reticulate bottom, and a receptacle for high explosives 60 above said second-mentioned receptacle and in communication therewith.

17. In a defense mine, the combination of a case, a hollow base in said case secured to its bottom and having a diaphragm dividing the hollow to provide a dead-air-space and a well thereabove, a receptacle for an ignitable substance above said base and with a reticulate bottom, a receptacle for quick ignition substance above said first-mentioned receptacle and provided with a reticulate bottom, and a receptacle for high explosives above said second-mentioned receptacle and in communication therewith.

OLIVER W. BOZZETT.
